APPARATUS FOR SCRIBE-MARKING
PACKAGE PRODUCTS

George C. Sanford, Ruston, La.

Application September 11, 1952, Serial No. 309,123

3 Claims. (Cl. 33—37)

1

This invention relates to a scribing apparatus for scribing markings such as lines or the like upon a predetermined portion or area of an article. More particularly, this invention relates to a scribing apparatus for marking a predetermined portion of a label for a food package or a wrapped bakery article to provide the label with significant packaging data.

It is very desirable to provide a method and means for marking the labels or packages for products, the age of which is of interest to the user, in such a manner as to indicate significant packaging data to anyone knowing the marking system. Such products include, for example, foods, pharmaceuticals, film supplies, and chemicals. For example, by practicing this invention it is possible to mark a wrapped loaf of bread in such a way as to indicate to anyone knowing the marking system the date of packaging. Various other data may be marked on such packaged goods, either alone or in combination with other data.

It has been proposed to employ scribing devices in applying markings to predetermined portions or areas of articles. One such scribe is shown in United States Patent No. 1,979,744 wherein there is disclosed a scribe for applying a linear mark to a shingle. This apparatus is limited, by virtue of its structure, to the application disclosed by the patentee and is not adaptable for scribing labels and like articles employed with wrapped or packaged materials which deteriorate in storage. It is also known in the art to place code markings directly on the wrapper of a packaged food or bakery product, but such means require comparatively complicated or expensive equipment. It is therefore a principal object of this invention to provide an improved, simple, and inexpensive scribing apparatus for scribe marking packaged products such as bread, pharmaceuticals, film supplies and chemicals in such a manner as to indicate significant packaging data.

A further object of this invention is to provide a scribing device adapted for use with packaging or wrapping machines, which scribing device includes an element for guiding labels or like articles along a fixed path, and a scribe marker which may be selectively positioned at a predetermined point between the marginal edges of the guided moving label or the like.

A still further object is to provide a scribing device for labels or the like which includes a bed for supporting labels, guide means associated therewith for guiding the labels in a fixed path,

2

pressure means for confining the labels within the guide means and a rotary scribing element which may be selectively positioned on a support extending transversely with respect to the fixed path of the labels.

The above objects and the novel features of my invention will become more apparent from the following detailed description and accompanying drawings showing one embodiment of my invention.

In the drawings, wherein like numerals designate like parts in the several views:

Figure 1 is a top plan view of a scribe constructed according to my invention mounted on a packaging machine of which only a fragmentary part is shown. A fragmentary section of a strip of labels threaded through the scribe is indicated in broken lines.

Figure 2 is a side elevation of the device of Figure 1.

Figure 3 is a partial section substantially along the line 3—3 of Figure 2, slightly enlarged, and with one trunnion bearing shown in section along a vertical plane through its axis.

Figure 4 is a slightly enlarged partial section through the line 4—4 of Figure 1.

Figure 5 shows a typical bread label with a scribed mark across it made in accordance with my invention.

Referring now to the drawings, the numeral 10 designates generally a scribing device mounted on an automatic bread packaging machine 11 which is indicated only by a fragmentary part, but which includes wrapping mechanism, label applying means, and label supplying means. In machines of this type labels may be fed or supplied individually or from one or more continuous strips, from which individual labels are severed for application to the wrapped loaves. Although my invention is applicable to machines in which the labels are fed individually, the embodiment shown in the drawings is better adapted for use in machines which use the strip form of label feeding, and numeral 12 indicates a strip of labels 13 threaded through my device in operative position for the scribing thereof. When labels 13 are fed to the scribing device in the form of a strip 12, the strip is pulled through the scribing device by the label supplying means of packaging machine 11. In this case the scribing device performs the additional function of supplying just the right amount of tension to the strip of labels to insure smooth feeding and insure proper sealing of the labels to the packages.

Numerals 14 indicate a label guide channel.

This guide channel may be a normal part of the label supplying means for wrapping or packaging machine 11, or it may be added in the path of the normal label supply means. In either case it is an integral part of scribing device 10. Guide channel 14 has means for supporting labels 13, such as bed portion 15, and means for guiding them along a fixed longitudinal path such as edge guides 16 on each side of bed portion 15.

Attached to either side of guide channel 14 are side plates 17 and 18 which serve to support and hold together the parts of scribing device 10.

Suitable supporting means are provided for mounting scribing device 10 on packaging machine 11, which may take the form of support 19, consisting of a downwardly turned extension 21 of label guide channel 14 with flanged end 22 adapted to be fastened to packaging machine 11 by screws 23; and of support 20, consisting of a transverse toe joining the lowermost points of side plates 17 and 18, this toe or support 20 simply resting on packaging machine 11.

There is a transverse opening 25, best seen in Fig. 4, in bed portion 15 which extends the full width of bed portion 15 between edge guides 16.

Mounted below opening 25 is a scribing member 26 which is in this instance a scribing wheel. Scribing wheel 26 is adjustably mounted on a spindle 27 which is positioned transversely with respect to the fixed longitudinal path of labels along guide channel 14. Spindle 27 is mounted for free rotation in trunnion bearings 28 and 29 which are removably mounted in side plates 17 and 18 respectively, as shown in Fig. 3.

As stated above, scribing member or wheel 26 is adjustably mounted on spindle 27. The adjustment is along the spindle, that is transversely with respect to the fixed longitudinal path of the labels 13, and is provided for as follows. Spindle 27 is threaded, as indicated in Fig. 3. Permanently attached to one side of scribing wheel 26, as by welding, is a nut 31 which is threaded to fit threaded spindle 27. By this means scribing wheel 26 may be placed in any desired position along spindle 27. A lock nut 32 on the other side of scribing wheel 26 provides means for clamping scribing wheel 26 in the desired position. Pivotaly mounted on shaft 33, which is in turn mounted in side plates 17 and 18, is an inking device 34 which includes an inked wick or pad 35 in contact with scribing wheel 26 as best shown in Fig. 4. Inking device 34 is mounted with center of gravity slightly offset with respect to shaft 33, with the lighter side in contact with wheel 26, so that inking device 34 is biased to engage the periphery of scribing wheel 26. A suitable slot 36 in side plate 18 provides means for removing and replacing inking device 34. This is convenient for shifting colors of ink, as well as for servicing.

Mounted above transverse opening 25 is a pressure roller 40, which is mounted on an axle 42 which fits in slots 41 in side plates 17 and 18 for free rotation about an axis parallel to that of spindle 27, and so mounted as to press labels 13 down against scribing wheel 26 as indicated at 43 in Figure 4. Slots 41 provide convenient means for lifting or removing pressure roller 40 when threading a strip of labels 12 through the scribing device.

In operation the scribing wheel is adjusted to a selected transverse position and locked there. Then the labels 13, preferably in strip form 12, are fed face down through scribing device 10.

Pressure roller 40 presses each label down against scribing wheel 26, which is inked by inking device 34, so that a line 50 is scribed across the label 13 in a predetermined area or position with respect to side edges 51.

Labels 13 may or may not have identically placed, transversely disposed indicia 52 on each label. When labels 13 have such indicia thereon it is easier and more accurate to observe the transverse position of line 50.

As an example of the use of this device in the method of code-marking packaged bakery products according to this invention, by pre-arrangement the six letters of the word "sliced" 15 may represent in sequence the days Monday through Saturday, and the prearranged code may provide that a scribed line be marked across the label immediately after the letter corresponding to the day of the week on which the product, 20 bread in this instance, is packaged. In this instance the line 50 on Figure 5 would indicate that the bread in the package to which label 13 is affixed had been packaged on Wednesday.

Although in the drawing scribing wheel 26 25 has been shown as having a sharp printing periphery lying in one plane so as to make a continuous straight line such as 50, it will be understood that the printing periphery may have any desired configuration, so as to produce different kinds of scribe lines, such as dotted lines 30 or wavy lines. Also any desired color of ink may be used. Such variations in character and color of the scribed line may be used to signify different kinds of data, and several kinds of data 35 may be marked on the same label by using the required number of scribing wheels, which may be mounted in the same scribing device or, preferably, in separate scribing devices through which labels 13 are passed in sequence prior to being affixed to the packaged product. Examples of 40 other data which can be indicated in place of or in addition to date of packaging are batch number, order number and lot number.

The use of an inked scribing wheel is not essential to the invention, as any form of scribe 45 marker may be used. It is possible to arrange the scribing member above the guide channel 14. The scribing member may be mounted in other ways for transverse positioning with respect to the path of the labels. The pressure roller and scribing wheel may be power driven, and a belt feed may be used in place of bed portion 15; modifications such as these will normally be used when labels 13 are to be fed to the scribing device separated from each other. Numerous other variations are possible within the scope of the appended claims.

It will be obvious that the apparatus according to this invention is also suitable for scribe-marking wrappers themselves in selected areas 60 to indicate significant data, or for similarly code marking inserts for packaged products.

I claim:

1. A scribing device for labels adapted to apply 65 a longitudinally disposed scribe mark along a predetermined line between the side edges of said label comprising, a supporting frame member, a guide channel mounted on said frame member, said guide channel including a bed portion and edge guides extending upwardly from each side of said bed portion for engaging the side edges of labels passing through said device and guiding said labels along a fixed longitudinal path, said bed portion being provided with a transverse 70 opening extending between said edge guides, a

gravity actuated pressure bearing roller mounted on said supporting frame above said bed portion for maintaining labels in contact with said bed portion adjacent the opening therein, a scribing member positioned below said bed portion and extending into the opening provided therein for contacting labels moving over said bed portion between said edge guides, a support for said scribing member mounted on said supporting frame and positioned transversely to said edge guides, said scribing member being movable on said support therefor transversely to said edge guides, and means for securing said scribing member to said support therefor at a predetermined point thereon whereby labels continuously fed longitudinally through said scribing device will be marked with a scribe mark longitudinally thereof along a predetermined line between the side edges thereof.

2. A scribing device as set forth in claim 1 wherein said scribing member consists of a narrow circular plate rotatably mounted on said support therefor and adapted to rotate in a plane coinciding with a longitudinal axis of the labels fed through said scribing device.

3. A scribing device as set forth in claim 2 wherein an elongated scribe inking means is pivotally mounted on said supporting frame below said scribe member, the mid-point of said inking means being disposed on the side of said pivotal mounting for said inking means remote from said scribing member.
